UNITED STATES PATENT OFFICE

137,050

DESIGN FOR A COMBINED FLOWER POT AND HOLDER

John W. Hill, Chicago, Ill.

Application August 16, 1943, Serial No. 110,929

Term of patent 14 years

To all whom it may concern:

Be it known that I, John W. Hill, a citizen of the United States and resident of Chicago, in the county of Cook and State of Illinois, have invented a new, original, and ornamental Design for a Combined Flower Pot and Holder, of which the following is a specification, reference being had to the accompanying drawing, forming a part thereof.

In the drawing,

I claim:

The ornamental design for a combined flower pot and holder, as shown.

JOHN W. HILL.
